Thomas Hubbard Morgan, Kittanning, and
Dwight C. Morgan, Jr., Oakmont, Pa.

Application August 29, 1945, Serial No. 121,707

Term of patent 14 years

(Cl. D9—2)

To all whom it may concern:

Be it known that we, Thomas Hubbard Morgan and Dwight C. Morgan, Jr., both citizens of the United States of America, and residents of Kittanning, Pennsylvania, and Oakmont, Pennsylvania, respectively, have invented a new, original, and ornamental Design for a Vacuum Cleaner Casing or Similar Article, of which the following is a specification, reference being had to the accompanying drawing, forming part thereof.

In the drawing:

Figure 1 is a perspective view of a vacuum cleaner casing or similar article showing our new design; and

Figure 2 is a transverse cross-sectional view of the vacuum cleaner casing or similar article shown in Figure 1.

We claim:

The ornamental design for a vacuum cleaner casing or similar article, substantially as shown.

THOMAS HUBBARD MORGAN.
